UNITED STATES PATENT OFFICE

HENRY F. WILMS, OF CLEVELAND, OHIO, ASSIGNOR TO INDUSTRIAL BROWNHOIST CORPORATION, OF BAY CITY, MICHIGAN, A CORPORATION OF OHIO

CONCRETE MIXER

Application filed January 28, 1931. Serial No. 511,828.

This invention relates to mixing drums used for mixing concrete and the like, and, more particularly, to the interior mechanism of such drums comprising blades, flights, or pick-up buckets.

A more ready comprehension of the invention may be had from a consideration of the difficulties encountered in constructing and operating concrete mixers equipped with the interior mechanisms now employed in the art. These mixers are of three general types; first, those that revolve only in one direction and have a mixing blade arrangement requiring the insertion of a discharge chute or spoon to discharge the contents when mixing has been completed; second, those in which it is necessary, in order to discharge the vessel, to tip the whole mixing drum at one end in order to permit the contents to flow out by gravity; and third, those in which the drum is made conical at the discharge end and the mixing blades extend along the inside of this cone to discharge the contents. It may be noted that, in this third type, the discharge arrangement is limited to one in which the angle of the sides of the cone with the horizontal is not greater than that at which concrete will flow by gravity, otherwise the mechanism will not discharge its contents fast enough to be commercially practical.

It will be appreciated that each of the three types of mixers defined above are subject to certain disadvantages in the operation of discharging the mixer, as, for instance, the necessity for the insertion of a separate element, a discharge chute, into the drum, the power necessary to tip the entire mixer where this method of unloading is used, or the limitations to the speed of discharge attainable with a conical discharge end. In addition, it is often desired to mount a concrete mixer on a motor truck and this has been done with each of the three types of mixers above mentioned. Where the vessel is so mounted, it

may be revolved either by its own power plant or by a properly designed mechanism driven by the engine of the motor truck. When the unit is thus made mobile however, further mechanical difficulties and limitations are encountered. For example, it is necessary above all that the weight of the mixer be kept down so as not to over-load the truck or limit its useful load, i. e. mixed concrete, since the road laws of the various States limit the gross load that may be carried on the highways. Another limitation on design is imposed by the necessity for locating the center of gravity of the mixer ahead of the rear wheels of the truck, otherwise the truck becomes unstable and, also, the various State laws are again encountered, which fix a definite percentage of the total load which may be carried on the rear axle. A longer mixer would therefore require a truck with a longer wheel base in order to bring the center of gravity forward of the rear wheels, but motor trucks with long wheel bases do not have the maneuverability of those with shorter wheel bases and are more expensive. Where mixed concrete is being delivered to the site of an office building located in the business section of a large city extremely little space is available for maneuvering a truck into position to unload, and lengthening the wheel base to stabilize a truck is, practically, not an available expedient. Another difficulty arises when the truck must be discharged from ground which is not level. If the truck is on a grade with the rear end higher than the front end a mixer of any one of the above three types will discharge too slowly and will take up time allocated to following trucks in the closely timed schedule which is necessarily established for the delivery of materials in modern city construction. If the grade is sufficiently steep, say a grade of 15 per cent, the mixer is prevented from discharging its entire load,

sometimes leaving almost one-half of the load remaining in the vessel.

Further mechanical difficulties encountered when a mixing drum is mounted on a truck follow from the custom of closing up both the charging and discharging openings of the mixer with a removable door or gate to prevent the drum from spilling its contents while mixing. This discharge door or gate causes the operating mechanism to increase in complexity when the discharge chute method of emptying the drum is used and also adds considerably to the weight. In the type of mixer in which the entire drum is tilted up to discharge, a hoist is required similar to those used on the dump bodies of trucks, which also adds considerably to the expense and weight and complicates the mixer.

Having in mind the above set forth disadvantages inherent in the various types of mixers in use at the present time, it is an object of my invention to provide an entirely new type of mixer drum which is more efficient in its operation under varying conditions, due to its simplicity and its freedom from moving parts. Another object of the invention is to provide a mixer which is more economical to construct and operate due to its light weight and low cost of manufacture. Still another object of the invention is to provide a mixer which may be discharged quickly on any grade likely to be encountered in actual use. A further object of my invention is to provide an entirely new type of mixing blade for mixing drums, the new type of blade avoiding the necessity for a discharge chute, tilting of the entire drum to discharge, or for a low-angle cone at the discharge end of the drum.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:—

Fig. 1 is a longitudinal vertical section taken along the center line of the mixer; Fig. 2 is an end elevation of the discharge end of the mixer drum; Fig. 3 is a transverse section taken along the line 3—3 of Fig. 5; Fig. 4 is a view in perspective of a part of the interior mechanism of a drum with a portion of the drum cut away; and Fig. 5 is a side elevation of the mixer mounted on a motor truck.

Concrete mixers, when mounted on a truck, are usually arranged to rotate in either direction, and it is the common practice to reverse the direction of rotation while

mixing in order to obtain a more thorough mixing of the ingredients. Discharge of the contents is usually accomplished, however, by rotating the drum in one predetermined direction, thus causing the blades to push the material towards the discharge opening.

Referring now to the drawings, there will be set forth hereinafter a description of the new and improved mechanism comprised by the invention and the manner in which mixing and discharge is accomplished thereby. In Fig. 1 a mixer drum 6 is of the conventional type and has attached to its inner surface one or more flights or blades 7. Toward the rear of the drum is found the blade 8 having its counterpart 9 in the half of the drum not shown, these blades having the double function of both mixing and discharging. A baffle 11 is attached to blades 8 and 9 and lies in a plane defined by the center line and a diameter of the drum. The opening 13 cooperates with a flared discharge or drip ring 14, which is usually used in combination with a door (not shown). The front head 15 of the drum is usually not provided with apertures, being left blind. The manner of attaching the flights 7, which may be termed auxiliary blades, since they assist the function of the blades 8 and 9, may be seen in Fig. 3.

Referring to Figs. 2 and 4 of the drawings, the blade arrangement characterizing my invention may be clearly seen therein. Blades 8 and 9 are located near the discharge end of the drum, being, in fact, attached to the discharge head of the drum at the ends 16 and 17 and being also attached to the inner wall of the drum at their outer edges 18 and 19. Each blade is inclined at an angle to the center line of the drum, this angle being, in the preferred form, approximately 45° , but it will be appreciated that the angle of the blades may be modified considerably to meet various operating requirements. The blades are also placed at an angle to each other, one sloping downwardly toward the rear of the drum and the other sloping downwardly toward the front of the drum when the apparatus is in the position shown in Fig. 4, their respective planes thus forming vertical angles with each other, since the blades are in diametrically opposite sides of the drum. The attachment of the blades to the wall of the drum may be by means of angle irons 12. The blades contact with the rear head of the drum on lines approximately tangent to the discharge opening 13.

Closely cooperating with the two blades 8 and 9 is the baffle 11, aforementioned, which is placed perpendicularly between the two blades, to the inner edges of both of which it is fastened by electric welding or other suitable means. It completely spans the space between the blades at the point of

their connection to the discharge head and assumes a vertical position when the blades slope toward the front and rear of the drum as described above. The position of the baffle 11, spanning the space between the blades at their rear ends and connecting the blades, is productive of highly important results, as will appear at length hereinafter.

In Fig. 5 may be seen various adjuncts, in addition to the truck shown, to the operation of the mixer, such as the charging opening 22, through which the mixer is charged and which is closed before the drum is revolved, and driving means 23 causing the drum to rotate through the driving gear 24. The rear end of the drum is rotatably mounted on the roller track 25. Water is carried in the tank 26 and is supplied to the concrete mix through the water bells 27.

The manner of operating the mixing drum is as follows: The drum is first charged with all the materials necessary for the formation of concrete or for whatever product it may be desired to mix in the apparatus. This may be done through the charging opening 22 or through the discharging opening 13, in the former case the drum being revolved until the opening 22 is on top, the material allowed to flow in, the doors closed and the drum started revolving. The drive for the drum is arranged so that the vessel can be revolved in either direction as desired. When it is desired merely to mix the materials the drum is revolved in the direction of the arrows 1 on Fig. 2 of the drawings, this direction being counter-clockwise when viewed from the discharge end. The material in the drum will be pushed toward the blind head of the mixer, the blades 8 and 9 and also the auxiliary blades 7 slicing through the mass and mixing it. When it is desired to reverse the movement of the aggregate the operator reverses the direction of rotation of the drum to that indicated by arrows 2 in Fig. 2 of the drawings and the material is pushed in the opposite direction toward the discharge end of the drum, the blades slicing through the material as before, but in the opposite direction. At the rear end of the drum the baffle 11, forming a pocket with the blade 9, carries some of the material toward the top of the drum, discharge through the opening 13 being prevented by a door kept normally closed during mixing. As this pocket continues to revolve, it passes the upper limit of retention of the material which drops out and the blade 8 directly opposite begins to pick up the material in a pocket, which it also forms with the baffle 11. It is therefore apparent that the material is picked up and dropped twice in each revolution by blades 8 and 9 in combination with the baffle 11, which results in a very thorough mixing of the ingredients and insures that there will

be no stratification of these while the mix is in transit.

When it is desired to discharge the contents of the mixer, the door at the discharge opening 13 is opened and the drum is revolved in the direction of the arrow 2, the blades 8 and 9 picking up the material and raising it until the angle of the blade with the horizontal becomes greater than the angle of repose of the material, whereupon the latter falls down the blade and out through the discharge opening. There is no possibility of the material flowing over the edge of the blade and returning to the bottom of the drum since the baffle 11 effectively prevents any movement of the concrete or other material except outwardly through the discharge opening. As the discharging operation proceeds it will be seen that all of the material in the drum will be forced forward into the pockets formed by the blades and baffle, by the auxiliary blade 7 and the blades 8 and 9 themselves and, once in these pockets, the material can take but one course, outwardly through the discharge opening. As a consequence the drum is very completely and quickly emptied of its contents, thus permitting the truck on which it is carried to be moved out of the way in a very short time. Since the concrete is raised by the pockets above the bottom of the drum, the drum can be discharged even though its rear end rests considerably higher than its front end. It is only necessary that the concrete be raised high enough to tumble out through the opening 13. No accessory parts are needed to discharge the drum, such as a discharge chute or a low-angle cone at the discharge end. Also, it is not necessary to elevate the entire drum. By avoiding all of these discharge devices the weight and length of the drum is cut down and a much more efficient mobile unit is provided than has heretofore been available.

So far as I am aware no type of blade arrangement or combination of blades has been used heretofore in concrete mixers or other apparatus of this nature. The blade construction is considered to be entirely new in the art and it is desired to claim the same in its broadest aspects whether used in conjunction with a mobile mixing unit or in a stationary unit.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a mixing drum the combination of two mixing blades, fastened to said drum and one of its heads, and a baffle fastened to said

head and extending therefrom on the drum's median plane between said blades and fastened to the same, said blades being oppositely inclined with respect to said median plane, and cooperating with said baffle and head to form pockets to collect and eject the mixed concrete from the drum.

2. In a mixing drum, the combination of two diametrically opposed and oppositely inclined blades attached to the shell of said drum and to one of its heads, of a baffle diametrically disposed between said blades and fastened to said head, said blades, baffle and head interconnected to form pockets to eject the mixed contents of the drum.

3. In a revolvable mixing drum, the combination of means for revolving said drum in either direction, a closable aperture in one of the heads of said drum, two diametrically opposed and oppositely inclined blades attached to the shell of said drum and to said head at points approximately tangential to said aperture, of a baffle diametrically disposed between said blades and fastened to the blades and to said head, said shell, blades, baffle and head interconnected to form pockets to agitate the contents of the drum during one direction of its rotation and to eject the same through said aperture during reverse rotation.

30 4. In a drum capable of being revolved and having an opening in the drum head, the combination of two diametrically opposed blades attached along their inner edges to opposite faces of a baffle placed perpendicularly between them, one of said blades sloping downwardly toward the rear of said drum and the other sloping downwardly toward the front of said drum when said baffle is in a vertical position, and the rear ends of said blades being attached to said drum head approximately on a tangent to said opening.

45 5. In a mixing drum, the combination of two mixing blades in said drum, said blades being diametrically opposed, attached to opposite sides of the drum wall at their outer edges and attached to opposite faces of a baffle placed perpendicularly between them at their inner edges, and the rear ends of said blades being approximately tangent to an opening in the rear head of said drum.

50 6. In a mixing drum, the combination of two mixing blades, and a baffle, said blades being attached to the wall of said drum and to opposite faces of said baffle, and said blades being oppositely inclined with respect to the center line of said drum, forming pockets with said baffle.

60 7. In a mixing drum, the combination of two diametrically opposed and oppositely inclined blades attached to the wall of said drum and to a baffle perpendicularly disposed between them, said blades and baffle forming pockets to eject the contents of the drum.

65 8. In a mixing drum capable of being revolved, the combination of means for revolv-

ing said drum in either direction, an opening in the head of said drum, two diametrically opposed and oppositely inclined blades attached to the wall of said drum and joined through a baffle perpendicularly disposed between them, said blades being attached at one end to the head of said drum approximately tangent to said opening, and said blades and baffle forming pockets to agitate the contents of the drum and to eject the same from said opening.

Signed by me, this 21st day of January, 1931.

HENRY F. WILMS.
